UNITED STATES PATENT OFFICE.

ROBERT MITCHELL, OF LONDON, ENGLAND.

ROLLER FOR SUGAR-CANE MILLS.

1,015,577.

Specification of Letters Patent.

Patented Jan. 23, 1912.

Application filed April 6, 1910. Serial No. 553,705.

To all whom it may concern:

Be it known that I, ROBERT MITCHELL, of the Sugar Machinery Manufacturing Company, a citizen of the United Kingdom of 5 Great Britain and Ireland, and resident at 76 Elsham road, London, West, engineer, have invented certain new and useful Improvements in and Relating to Rollers for Sugar-Cane Mills, of which the following 10 is a specification.

This invention relates to improvements in rollers for sugar cane mills.

My present improvements are developments in the art and consist in forming—in 15 any manner—the face or body of the roller with a series of indentations of a square, rectangular, hexagonal or any other shape, except round indentations.

In the drawings I have shown certain 20 different shapes of indentations, for example:—

Figure 1 illustrates a roller having square stepped indentations; Fig. 2 being a sectional view through the indentations. Fig. 25 3 a roller with hexagonal stepped indentations; Fig. 4 being a sectional view of the indentations. Fig. 5 a roller with square indentations similar to Fig. 1 but arranged differently; Fig. 6 being a sectional view 30 through one of the indentations. Fig. 7 a roller with indentations of a trapezoidal shape; Fig. 8 being a sectional view through the indentations. Figs. 9, 10 and 11 are certain other designs of indentations.

In Fig. 1, A shows square or rectangular 35 indentations stepped thrice as shown at *a*. Fig. 2. In Fig. 3, B shows hexagonal stepped indentations thrice stepped as shown at *b*. Fig. 4. In Fig. 5 thrice stepped indentations C as shown at *c* Fig. 6; but with the

indentations arranged differently to Fig. 1. In Fig. 7 thrice stepped indentations D as shown at Fig. 8, of a trapezoidal shape. Either or any one of the indentations may have at their base a cone such as *e* Fig. 9. 45 Or the indentations may be formed in the face or body of the roller without stepping, that is to say something after the manner as shown at *f* Fig. 10. The indentations such as shown at *f* Fig. 10 may also have 50 a cone such as *g* Fig. 11. Any other shape of indentations may be employed—except round—and the indentations may have any number of steps and they may have cones at their base; or the cones may be dispensed 55 with.

It is found by practical experience that the corners produced by indenting the face or body of the roller, bite the cane very effectively and no slipping of the cane occurs.

The rollers can be rotated in any direction that is to say clockwise or counter-clockwise and they are equally effective 60 when rotated in either direction. 65

Claim—

1. Rollers for sugar mills provided with a plurality of polygon shaped indentations on the surface, each indentation being formed by a plurality of square cornered 70 steps.

2. Rollers for sugar mills provided with a plurality of polygon shaped indentations on the surface, each indentation being formed by a plurality of square cornered 75 steps and with convex bottom.

ROBERT MITCHELL.
